Edmond Conger Brown

ATTORNEY

UNITED STATES PATENT OFFICE.

HENRY GOWER HOSE, OF BROOKLYN, NEW YORK.

BUTT-END COMPOSITION-SHINGLE FOR ROOFING AND THE LIKE.

1,310,082.

Specification of Letters Patent.

Patented July 15, 1919.

Application filed October 3, 1917. Serial No. 194,500.

To all whom it may concern:

Be it known that I, HENRY GOWER HOSE, a citizen of the United States, and a resident of the borough of Brooklyn, in the city and State of New York, have invented certain new and useful Improvements in Butt-End Composition-Shingles for Roofing and the like, of which the following is a specification.

10 My invention relates to shingles used for roofing and the like, and has for some of its principal objects to provide a composition shingle which when in place shall present a more pleasing and attractive appearance than is presented by forms of composition shingle hitherto employed, and of which a comparatively cheap, but durable and effective roof may be constructed. Other objects of my invention and some of the advantages 20 thereof will be hereinafter set forth.

The invention consists in the novel construction, arrangement and combination of various elements and parts, as shown in the accompanying drawings and hereinafter 25 more particularly described.

In the said drawings, Figure 1 represents a perspective view of a roof employing my improved butt end composition shingle, a portion of said roof being broken away to 30 show the furring strips which may be used to support the same; Fig. 2 is a view on an enlarged scale of a form of my improved roofing in which several shingles are integrally constructed; Fig. 3 is a view, also on 35 an enlarged scale, showing the same in the relative positions which they occupy when laid, and Fig. 4 is an enlarged section showing the invention in detail.

In carrying my invention into effect in the 40 embodiment thereof which I have selected for illustration in the accompanying drawings and description in this specification. I provide a foundation consisting of a sheet of felt or the like, 10, saturated with asphalt or other suitable moldable substance, and coated on its upper side with a layer of asphalt 11 in which is embedded a coating of chipped or crushed slate or similar material 12, as shown in the drawings.

45 The sheet of felt so treated is then cut up into pieces of the proper size and shape to be used as shingles, either singly, or in the form of notched strips which when laid will present the appearance of several shingles, 50 as shown in Figs. 2 and 3. The under side of the sheet of felt is then coated with a layer

of asphalt designated 13, or of asphalt and asbestos mixed, or of any other substance or substances having similar properties, and being also more or less moldable; the said 60 layer being of variable thickness, that is to say, of a wedge or other irregular shape, being heaviest at the bottom of the shingle, forming a butt-end, and tapering off evenly or by steps or in any desired manner to the 65 top thereof. If desired, this added layer need not extend the whole length of the shingle, but may occupy only the lower end portion, extending up say one-third of the distance, as the principal function of the 70 layer is to form the thickened or butt-end.

75 My improved butt end composition shingle may be applied to a roof preferably by nailing each row thereto through the thin upper portion of the shingle, as will be obvious, or in any other suitable manner. The successive rows are then laid one over the other as shown in Fig. 3, working up toward the ridge of the roof, as with ordinary shingles, the rough slate surface forming the upper 80 part of each layer being in contact with the comparatively plastic or moldable and more or less adhesive substance on the lower surface of the incumbent layer, the result being that the successive layers tend to cohere and, 85 after a short time, form a more or less homogeneous and integral roof covering.

The advantages of my invention will be 90 obvious. I might particularly call attention to the attractive and pleasing appearance presented by the shingles, the butt-ends of which are large enough to be seen from a considerable distance; the fact that the asphalt on the lower side of each shingle will adhere, as above set forth, to the slate on 95 the upper face of the shingle beneath, thereby preventing water from blowing up under the shingles; and the fact that the thick butt end will prevent the lower ends of the shingles from buckling or curling up, and from 100 flapping in a wind; and the fact that the shingle is strong enough and has sufficient body to dispense with the necessity of laying the same over a full boarded surface, thus 105 saving on the cost of the roof by permitting the use of furring strips, such as shown in Fig. 1 and designated 14.

Having thus described my invention, what I claim as new and desire to secure by Letters Patent is as follows:

110 A butt-end composition shingle comprising an intermediate layer of felt, an upper

layer of asphalt adhering to said felt layer and having embedded therein a layer of chipped slate, and an under layer of moldable material adhering to the undersurface 5 of said layer of felt, said layer of moldable material being thick at its lower end and forming the butt-end of the shingle and tapered upward therefrom in thickness, the

moldable material of said under layer being adapted to unite with the chipped slate surface of an underlying shingle to form a one-piece roof. 10

In witness whereof I have hereunto signed my name this 28th day of September, 1917.

HENRY GOWER HOSE.
